UNITED STATES PATENT OFFICE.

FOLKE W. WESTON, OF NEW YORK, N. Y., ASSIGNOR TO F. WESEL MANUFACTURING COMPANY, OF BROOKLYN, NEW YORK, A CORPORATION OF NEW YORK.

PLATE-HOLDING DEVICE.

1,076,928.

Specification of Letters Patent.

Patented Oct. 28, 1913.

Application filed March 31, 1911. Serial No. 618,050.

To all whom it may concern:

Be it known that I, FOLKE W. WESTON, a citizen of the United States, and a resident of the borough of Brooklyn of the city of New York, in the State of New York, have invented certain new and useful Improvements in Plate-Holding Devices, of which the following is a specification.

The invention is directed to new and useful improvements in devices for holding and positioning printing plates, which devices comprise a base and a plate engaging member held in place thereupon by the operating means for the member.

It also relates to a device having a base provided with a series of parallel slotted portions provided with plate engaging or clamping means that can be readily positioned at any point on the base and which also can be readily removed therefrom.

As showing specific embodiments of the invention reference is made to the drawings forming a part of the specification and in which—

Figure 1 shows in plan a view of a base having supported thereupon a printing plate held in place by means engaging the plate. Fig. 2 is a vertical sectional view taken on a line 2—2 of Fig. 1 looking in the direction of the arrows. Fig. 3 is an enlarged sectional view showing the relative position between the screw operating means and the plate engaging member prior to the former being drawn into operative position by a pin. Fig. 4 is an enlarged vertical sectional view through the slotted portion and showing the operating screw, plate engaging member, split pin and a portion of the base. Fig. 5 shows a sectional register hook embodying one phase of the invention, having a rectangular base part of which has been removed and a plate engaging or clamping member in which the pin always remains in place therein. Fig. 6 is an end view of the sectional register hook shown in Fig. 5. Fig. 7 is a side view of a plate clamping member having a screw operating member secured in place by a split pin which cannot be completely withdrawn from the clamping member. Fig. 8 is a plan view of the pin shown in Fig. 7. Figs. 9 to 12 are detail views of the threading mechanism employed for cutting the sections of screw

threaded teeth with the work indicated by broken lines.

55

In the devices illustrated in Figs. 1 to 4, 1 is the base having formed therein a series of parallel slotted portions 2, each having overhanging portions 3, the adjacent lower edges of which are provided with sections 60 of screw threaded teeth 4. There is located in the slotted portion a screw operating member 5 and the lower part of each of the slotted portions are recessed or cut away sufficiently to permit this member to move 65 transversely from engaging position with the teeth to the bottom of the slot whereby the same will be free to move longitudinally therein without engagement with the teeth on the overhanging portion. It will furthermore be observed from an inspection of Fig. 4 that the lower portion of the slot is 70 enlarged so that its transverse dimension immediately below the threaded sections is larger than the outside dimension of the 75 screw operating means 5 or larger than the largest diameter of the screw threaded sections in the base thus affording a construction which practically eliminates the clogging of the slotted portion in the base by 80 ink and dirt. Also extending into the slotted portion are the lugs 7 and 8 of the plate engaging or clamping member through which a split pin 9 for holding the screw operating member in operative position 85 passes. The lugs 7 and 8 are preferably the same width as, or at least not wider than the distance between the adjacent surfaces of the overhanging portion (see Fig. 4) 90 whereby the plate clamping member can be removed from the base by transverse movement when not held in place by the pin 9.

In the form shown in Fig. 3 it will be observed that both the screw operating member 5 and the pin 9 are beveled and the 95 depth of the slots in the base are such that when the plate engaging member 6 is brought in position over the screw operating member the pin 9 can pass through the opening in the lug 7 pick up the screw operating member and bring it into operative engagement with the teeth 4, and then pass the rest of the way through the opening in the screw operating member to the opening in the other lug 8 and in this manner hold 100 105 the screw operating member in place where

it can serve as means for holding the clamping member on the base and also as means for positioning the plate engaging or clamping member relative to the base. The movement of the screw operating member 5 is effected by means of a hand operating tool such as is illustrated in Fig. 5. In the form shown in Fig. 3 the split pin 9 can be entirely withdrawn from the plate clamping member at the will of the operator. The structure shown in the modified form illustrated in Figs. 7 and 8 is substantially the same as that shown in Fig. 3 with the exception that the pin 9^a has a recessed portion 9^b into which a pin 10 enters and due to this construction the split pin is prevented from being withdrawn entirely from the plate clamping member.

In Figs. 5 and 6 there is disclosed what is known in the trade as a "sectional register hook" comprising a small base 11 having a slotted portion provided with sections 12 of screw threaded teeth on opposite sides. A plate clamping or engaging member 13 having lugs or ears 14 and 15 is held in place on the base by the screw operating member 16. In this register hook it will be observed that the entire thrust from the clamping member or hook 12 is transmitted through the pin 17 and screw member 16 to the base and this affords a simple and practical construction and avoids close fits between the clamping member and base as for instance are necessitated by a construction like that shown in my patent for Register hooks No. 930,582, dated August 10, 1909 in which the thrust from the hook is directly absorbed by the base and where the screw operates only as a means for moving the plate engaging member along the slot, and for maintaining it in a certain position therein.

In Figs. 9 to 12 there is illustrated the tool which is employed for cutting the sections of screw threaded teeth upon opposite sides of the slot. This tool comprises a frame 18 having secured at its central portion a tap 19, the cutting portion of whose teeth is spirally arranged in such manner that the teeth at the forward end of the tap will be in engagement with the metal in the overhanging portion at one side of the slot while teeth in the same row and at the rearward end of the tap are in engagement with the metal of the overhanging portion at the opposite side of the slot. The teeth of the tap are also so arranged that those which are at the end of one row will be in engagement with the metal at one side of the slot while the teeth at the rear end of the succeeding row are in engagement with the metal at the same side of the slot. It will therefore be apparent that the tap always engages and is cutting metal at opposite sides of the slotted portion and in this manner the chatter which would take

place if the flutes of the tap were straight is eliminated and perfect teeth sections can be formed.

The frame carrying the tap comprises a longitudinally extending member 20, and transversely extending members 21 supporting the lugs 22 by which the tap is carried. Adjustably secured to each of the transverse members 21 by means of the vertical and horizontal screws 23 and 24 are the work engaging plates 25 which serve as means for regulating and adjusting the position of the tap relative to the work. At the opposite ends of the longitudinally extending member there are detachably secured by means of screws 26 the guide member 27 arranged so as to enter the slotted portion to be tapped or operated upon and these guide members serve as means for maintaining the work and tool in the proper relative position to each other during the travel of the frame over the work.

In order to carry out the proper cutting of the teeth it is apparent that the connections between the tap and the frame must be such that the tap can be firmly held in position against the work and at a definite distance from the outer surface of the base.

It is obvious that various forms and modifications may be made both in the devices for holding and positioning a printing plate and also in the apparatus and manner of making the screw threaded portions therein without departing from the spirit and scope of my invention.

I claim as my invention:

1. In devices of the class described the combination of a base having a longitudinally extending slotted portion provided with overhanging portions adapted to be engaged by an operating and holding means in the slotted portion, operating and holding means and a plate clamping member having ear portions entering the slot whose width is not greater than the transverse dimension between the adjacent surfaces of the overhanging portions whereby when disengaged from the holding means the clamping member can be removed from the base by a transverse movement relative thereto, the holding means comprising a member that simultaneously engages under sides of the overhanging portions at opposite sides of the slotted portion.

2. In a device of the class described the combination of a base having a longitudinally extending slotted portion provided with overhanging portions having parts of screw threaded teeth thereupon, a screw threaded operating member adapted to mesh with the toothed portion, the slotted portion being so shaped and of sufficient area in cross section as to permit transverse movement of the member to cause disengagement of the teeth and member and as to permit

free longitudinal movement of the member past the teeth when the teeth and screw threads are disengaged, and a plate clamping means provided with ears of such width that it can be inserted in place on the base by a transverse movement, the screw member when held in operative position relative to the hook being in engagement with the teeth of the overhanging portions at opposite sides of the slot.

3. A device of the class described having a base provided with a longitudinally extending slotted portion to receive a screw operating means and provided with teeth, screw operating means, a plate engaging or clamping member provided with ears or lugs of such construction that they can be assembled with the base by a movement transverse to the slotted portion and a pin, the slotted portion and screw means being so proportioned that the latter can move transversely from operating position to a position where it can be slid along the slot without engagement of the screw threads with teeth on the slotted portion, the screw member having a central hole therein and the ears having holes through which the pin can pass to hold the screw in operative position, the pin and the screw member having tapered or beveled portion or portions so that when the plate engaging member is in proper position relative to the screw the latter will be drawn into operative position by passing the pin longitudinally through the holes in the lug.

4. The combination of a base provided with teeth and having a longitudinally extending slotted portion; a plate engaging member having lugs entering the slotted portion, a screw operating member constructed so as to mesh with the teeth, and a slideable pin carried in the lugs and prevented from being removed entirely therefrom by stop means, said pin arranged to hold the screw means in operative position relative to the lugs.

5. In a device of the class described the combination of a slotted base, a screw member and a plate engaging member having ears entering a slot in the base the slotted base portions having teeth with which the screw member engages, the ears constructed so that they can hold therebetween a screw member, the width of the ears being such that

the plate engaging member can be removed from the base by a transverse movement relative thereto.

6. In a device of the class described the combination of a base having slotted portions provided with overhanging sides having integral therewith sections of screw-threads terminating short of the bottom of the slots, each of said slotted portions having an enlarged portion at the bottom whose transverse interior dimension is greater than the largest diameter of the screw-thread sections and said enlarged portion being sufficiently large to permit a screw which engages said screw-thread sections to move freely along said slotted portion when the screw is disengaged from said threads.

7. In a device of the class described the combination of a screw operating member and a base having slotted portions provided with overhanging sides, said overhanging sides having integral therewith sections of screw threads terminating short of the bottom of the slots, each of the sections of screw threads having a full depth of tooth from end to end of the section, the screw operating member normally engaging said screw-threads and the overhanging portions at the sides of the slot providing a clearance space between the screw and base for the reception or collection of ink, dirt or the like which would otherwise obstruct the movement of the screw.

8. In a device of the class described the combination of a screw operating member and a base having an inverted T-shaped slot provided at the junction of the inner end of the horizontal portions and the lower end of the vertical portions with sections of screw threads forming a series of teeth integral with the base, said screw member when in operating position engaging said sections of screw threads and the horizontal portion of the T-shaped slot being greater than the diameter of the screw member, thus affording a receiving space for any dust or dirt that may collect in the slotted portion.

This specification signed and witnessed this 28th day of March A. D., 1911.

FOLKE W. WESTON.
